UNITED STATES PATENT OFFICE

2,083,523

VENETIAN BLIND

Julius Nisenzon, Brooklyn, N. Y.

Application March 6, 1936, Serial No. 67,499

20 Claims. (Cl. 156—17)

This invention relates generally to improvements in window blinds of a class known as Venetian blinds, and more particularly to improvements in the head-piece therefor.

5 An object of the present invention lies in the provision of structure whereby the tape carrying tilt plates together with the elevating cord guides may be independently adjusted as a unit with respect to the head-piece or casing.

10 Where head-piece casings having provision for longitudinal adjustment (for example those described in my copending applications filed November 26, 1935, and bearing Serial Numbers 51,637 and 51,638) are utilized in conjunction with non-15 adjustable cut-to-measure slats, it has been found necessary to carefully determine and to accurately cut, with relation to the terminals thereof, the openings or slots in said slats through which the elevating cords will pass. This operation must be individually calculated and performed for each window, because as the effective length of the casing is varied by adjustment, the elevating cord guides are altered in distance from the new ends of the casing. All of this makes it necessary 20 to determine the position which the elevating cords and guides therefor will take when the blind is installed and to correspondingly shift the position of the slots in the slats.

By means of the present invention, however, 30 it is possible to utilize slats which although cut to length are provided with elevating cord openings or slots which are placed at a uniform predetermined distance from the slat terminals regardless of the length of the particular slat. Such a practice permits of economies in the manufacture of the slats and makes the proper installation of the complete blind a simple matter.

Another object of this invention is the provision of structure whereby the tape carrying tilt plates and elevating cord guides may be independently adjusted as a unit after the head-piece or casing is installed and without removing same from the retaining brackets therefor. This permits a visual examination and a very fine 40 and accurate manual adjustment while the blind is in place at the window so that any peculiarities of the particular window installation may be rapidly compensated for, and this without any special skill.

50 An advantage of the present structure is that the operation of the tilt plates therein is undisturbed by the shifting of said structure and said tilt plates may be of the driven type or of the idler type as disclosed in my copending application filed November 16, 1935, Serial Number 50,122.

Another advantage lies in the novel structure of the elevating cord guide which combines lightness, strength and simplicity, making for economical manufacture.

These objects, further features, incidental ends and advantages will more fully appear in the progress of this disclosure and as pointed out in the appended claims.

In the accompanying drawing, similar reference characters designate corresponding parts throughout the several views in which:

Figure 1 is a fragmentary front elevational view of the right hand end of a head-piece casing containing a preferred embodiment of the invention, with the front wall of said casing being broken away. In this view the casing is shown as installed on a relatively narrow window casement.

Figure 2 is a view similar to Figure 1 with the end latching plate extended, however, and the elevating cord guide assembly shifted in position. In this view the casing is shown as installed on a relatively wide window casement.

Figure 3 is a fragmentary plan view showing a portion of the head-piece casing, the elevating cord guide and tilt plate assembly with the tilting rod and elevating cords omitted for purposes of clarity.

Figure 4 is a fragmentary horizontal sectional view of Figure 1 taken along the plane 4—4 thereon with the elevating cords omitted.

Figure 5 is a transverse vertical sectional view of Figure 1 taken along the plane 5—5 thereon.

In the drawing it will be noted that only the right hand upper corner of a Venetian blind is shown. It will be understood that since both ends of the headpiece are correlative and similar in construction except that one may be described as a left hand end as distinguished from a right hand end, it is believed that the illustration of one end of the head-piece with elevating cord and slat tilting assembly therein will be sufficient for any one skilled in the art to which this invention pertains to understand my invention.

The head-piece frame or casing indicated generally by numeral 10 is substantially U shape in cross section (see Fig. 5), and is comprised of a base 11, a rear wall 12, a front wall 13 and an extendible latching plate 14. The casing 10 is adapted to be placed within a pair of mounting brackets 15 and to be locked in place by engagement of plates 14 with the latching flanges 16.

The tilt plate and elevating cord guide assembly is indicated generally by numeral 17. A pair of oppositely disposed right angle plates 18 are secured together by a pair of opposed vertical 55

plates 18, each of said plates 18 having a pair of right angle bent terminals 20. Each of the plates 18 is provided with a rectangular orifice 21 formed by making a "U" shaped cut in each plate and bending up the tab 22 until same is at right angles thereto. The terminals 20 are passed through the orifices 21 and then secured to the outer surfaces of plates 18 in any suitable manner as for example by spot welding at the points indicated by numeral 23. The pairs of plates 18 and 19 thus form an integral unit as best seen in Figure 4.

A roller or pulley 24 is trunnioned in and between plates 19. In order to simplify the assembly, pulley 24 is preferably provided with an integral axle 25 and the terminals of axle 25 are inserted in suitably disposed orifices in plates 19 prior to the welding operation recited above. After the welding is completed, removal of pulley 24 is thus positively prevented.

Plates 18 and associated parts are maintained in position by screws 26 which penetrate the slots 27 in base 11 and threadedly engage the horizontal portions of plates 18.

A tilt plate 28 is provided with a pair of tilting tapes (only one of said tapes indicated by numeral 29 being shown on the drawing, in Fig. 1) which support and tilt the plurality of slats ordinarily employed in the Venetian blind, only the top slat 30 being shown in the drawing. The tilting tapes are maintained in position by clamping bars 31 which are operated by screws 32 in threaded engagement with tilt plate 28. A pair of downwardly bent right angle ears 33 integral with plate 28 are mounted between plates 18 and upon a tilt rod 34. Rod 34 penetrates aligned orifices in the vertical portions of plates 18 and in the ears 33. Rod 34 is preferably provided with an irregular circumference as for example a plane side as indicated by numeral 35 on Fig. 5. In this manner, when it is desired to rotate the tilt plate 28 with the rotation of rod 34, the ears 33 may be suitably orificed to correspond to the circumference of the rod 34 and thus be keyed thereto, or conversely, when it is desired that the tilt plate 28 rotate freely about rod 34, the orifices in ears 33 may be circular as shown in Figure 5. Rod 34 may be rotated by any suitable means known in the art and the same is considered as not being important to the present disclosure and therefore is not specifically described or illustrated. It is to be noted however, that the adjustments described below are performed without altering the position of the rod 34 with respect to the headpiece 10.

An elevating cord 36 is fastened at the lower end thereof to a weight bar (not shown) well known in the art, and said cord passes through transverse slots 37 in the slats 30. It is the uniform placement of slots 37 with relation to the terminals of slats 30 regardless of the window casement width which constitutes one of the objects of this invention. Cord 36 leaving top slat 30 passes upwardly through the large rectangular orifice 38, between plates 19, contacts pulley 24, through orifice 21, over a roller 39, and thence downwardly through an orifice (not shown) in base 11. Roller 39 is rotatably mounted on casing 10 and any suitable means known in the art may be utilized for locking cord 36 in any displaced position thereof.

Another elevating cord 40 comes from an assembly similar to assembly 17, and located at the opposite end of the headpiece 10 and passes through the both orifices 21 and thence down-

wardly over roller 39. The cord 40 is protected from undesirable abrasion by the rounded smooth surfaces it contacts, namely terminals 20, tabs 22 and pulley 24.

The use and operation of the invention is as follows: Slats 30 are cut to the desired length to fit the particular casement, and are then slotted at 37 a predetermined distance from the ends thereof, as for example 6 inches which is present common practice. The entire blind is assembled and the brackets 15 put in place on the casement. The head-piece 10 is then installed in the brackets 15 and properly centered, and the plates 14 are latched behind flanges 16. Screws 26 are next loosened and the assembly 17 is manually shifted (preferably by pushing the opposed inner vertical faces of the plates 18 with the fingers of the hand penetrating the orifice 38) until the cord 36 passes unrestrictedly through the slot 37 and the ends of the slats 30 are equidistant from the adjacent vertical portions of the window casement. Tightening screws 26 securely locks the assembly 17 in place. Since the whole assembly 17 is moved as a unit, the elevating cord is always concealed by the tapes 29 and is properly centered therebetween.

The length of the slots 27 and orifice 38 is largely determined by the amount of variation permitted in the effective length of the head-piece or casing 10, which is in turn determined by the particular means employed for varying the effective length of said head-piece or casing; the means shown in the present disclosure being for purpose of illustration only.

The various adjustments outlined above are required only once when the Venetian blind is first installed in a given window casement. Subsequent removal or replacement requires only the manipulation of the latching plates 14.

The foregoing disclosure is to be regarded as descriptive and illustrative only, and not as restrictive or limitative of the invention, of which obviously an embodiment may be constructed including modifications without departing from the general scope herein indicated and denoted in the appended claims.

Having thus described my invention, what I claim as new and desire to secure by Letters Patent, is:

1. In a Venetian blind, a casing and an elevating cord guide longitudinally shiftable with relation to said casing.

2. In a Venetian blind, a casing and a tilt plate longitudinally shiftable with relation to said casing.

3. In a Venetian blind, a casing, and an elevating cord guide and tilt plate assembly, said assembly being in shiftable longitudinal relation with said casing.

4. In a Venetian blind, a casing having an orifice therein through which an elevating cord may pass, and an elevating cord guide longitudinally shiftable with relation to said casing.

5. In a Venetian blind, a casing having an orifice therein through which tilting tapes may pass, and a tape tilting means longitudinally shiftable with relation to said casing.

6. In a Venetian blind, a casing having an orifice therein through which an elevating cord and tilting tapes may pass, and an elevating cord guide and tilt plate assembly, shiftable with relation to said casing, in a longitudinal direction.

7. In a Venetian blind, a casing, and an elevating cord guide longitudinally shiftable with

relation to said casing, including means to fix the said guide in any adjusted position thereof.

5 8. In a Venetian blind, a casing, and a tilt plate longitudinally shiftable with relation to said casing, including means to fix the said tilt plate in any longitudinally adjusted position thereof.

10 9. In a Venetian blind, a casing, and an elevating cord guide and tilt plate assembly longitudinally shiftable with relation to said casing, including means to fix the said assembly in any longitudinally displaced position thereof.

15 10. In the Venetian blind, the combination of a casing having the effective length thereof adjustable, with an elevating cord guide longitudinally shiftable with relation to said casing.

20 11. In a Venetian blind, the combination of a casing having the effective length thereof adjustable, with a tilt plate longitudinally shiftable with relation to said casing.

25 12. In a Venetian blind, the combination of a casing having the effective length thereof adjustable, with an elevating cord guide and tilt plate assembly longitudinally shiftable with relation to said casing.

30 13. In a Venetian blind, an elevating cord guide including a vertically disposed plate having an orifice formed therein and an integral angle tab disposed substantially parallel with the direction of travel of an elevating cord passed through said orifice and whereby said cord will ride against said tab which constitutes a surface of reduced frictional and abrasive qualities.

35 14. In a Venetian blind, an elevating cord guide including a pair of oppositely disposed vertical plates, each of said plates having an orifice formed therein and an integral bent tab disposed substantially parallel with the direction of travel of an elevating cord passed through one of said orifices and whereby said cord will ride against said tab which constitutes a surface of reduced frictional and abrasive qualities.

40 15. In a Venetian blind, an elevating cord guide including a pair of oppositely disposed angle plates, each of said angle plates having an orifice formed therein, a pair of opposed vertical plates disposed at right angles to the said angle plates and having the terminals of said vertical plates supported by the angle plates.

45 50 16. In a Venetian blind, an elevating cord guide, including a pair of oppositely disposed angle plates, each of said angle plates having an orifice formed therein and an integral tab, a pair of opposed vertical plates disposed at right angles to and between the vertical portions of said angle plates and having the terminals of

said vertical plates supported by the angle plates.

5 17. In a Venetian blind, an elevating cord guide comprising a pair of oppositely disposed angle plates, each of said angle plates having an orifice formed therein, a pair of spaced vertical plates disposed at right angles to and between said angle plates, terminals on said vertical plates, said terminals being bent back around edges of the said orifices, whereby an elevating cord passed through one of said orifices and against said terminals, will ride against a surface of reduced frictional or abrasive qualities.

10 18. In a Venetian blind, an elevating cord guide comprising a pair of oppositely disposed angle plates, each of said angle plates having an orifice formed therein and an integral tab turned back at least 90 degrees therefrom, a pair of spaced vertical plates disposed at right angles to and between said angle plates, terminals on said vertical plates, said terminals being bent back around edges of said orifices, whereby an elevating cord passed through one of said orifices and against said tab or said terminals will ride against a surface of reduced frictional or abrasive qualities.

20 25 19. In a Venetian blind, an elevating cord guide comprising a pair of oppositely disposed angle plates, each of said angle plates having an orifice formed therein and an integral tab turned back at least 90 degrees therefrom, a pair of opposed spaced vertical plates disposed at right angles to and between said angle plates, terminals on said plates, said terminals being bent back around edges of the said orifices, a roller trunnioned between said vertical plates, whereby a cord passed through one of said orifices and against either said tab or said roller or said terminal will ride against a surface of reduced frictional or abrasive qualities.

30 35 20. In a Venetian blind, an elevating cord guide and tilting plate unit assembly comprising a pair of oppositely disposed angle plates, each of said angle plates having an orifice formed therein and an integral tab turned back at least 90 degrees therefrom, a tilting plate pivotally mounted between and supported by the upper portions of the angle plates, a pair of opposed spaced vertical plates disposed at right angles to and between said angle plates and below said tilting plate, terminals on said plate, said terminals being bent back around the edges of said orifices, a roller trunnioned between said vertical plates, all substantially as shown and described.

JULIUS NISENSON. 55
